Primary Examiner — Lauren D McVey*Assistant Examiner* — Mai Shim(74) Attorney, Agent, or Firm — Jose Cherson Weissbrot(57) CLAIM

The ornamental design for a toilet brush, as shown and described.

DESCRIPTION

FIG. 1 is a first perspective view of a toilet brush showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 7.

The evenly-spaced broken lines in the drawings depict portions of the toilet brush that form no part of the claimed design; The short-dash-long-dash broken lines indicating an enlargement portion of the design form no part of the claimed design.

1 Claim, 10 Drawing Sheets(56)
